UNITED STATES PATENT OFFICE.

FRANK R. MOORE, OF CUYAHOGA FALLS, AND EDWARD McSWEENEY AND CHARLES SCHLEY, OF AKRON, OHIO.

CAR-COUPING.

SPECIFICATION forming part of Letters Patent No. 670,055, dated March 19, 1901.

Application filed January 24, 1901. Serial No. 44,618. (No model.)

To all whom it may concern:

Be it known that we, FRANK R. MOORE, of Cuyahoga Falls, and EDWARD McSWEENEY and CHARLES SCHLEY, of Akron, in the county 5 of Summit and State of Ohio, citizens of the United States, have invented a certain new and useful Improvement in Car-Couplings, of which the following is a specification.

Our invention has relation to improvements 10 in car-couplers of the Janney type or commonly recognized as vertical-plane couplers.

The objects of our invention are to prevent the draw-head from being pulled out and falling on the track if it shall be detached or 15 broken from sudden shock incident to starting or stopping the train or other cause and to cause the breaking of the draw-head attachment to uncouple the car where the break occurs, so that when air-brakes are used the 20 car and the portion of the train back of it will be brought to a stop and the engineer notified; and a further object is to provide simple devices to secure the foregoing ends that 25 may be with slight attachments readily secured to the couplers now in use.

To the aforesaid objects our invention consists in the peculiar and novel construction, arrangement, and combination of parts hereinafter described and then specifically pointed 30 out in the claim, reference being had to the accompanying drawings, forming a part of this specification.

In the accompanying drawings, in which similar letters of reference indicate like parts 35 in the different views, Figure 1 is a plan of a coupler and connected parts, illustrating our invention, with a portion of the car-front shown in horizontal section; and Fig. 2, a side elevation of the same.

Referring to the figures, *i* is the draw bar 40 and head of the coupler, in which is pivotally mounted the knuckle *r*, having a rearwardly-extended arm at substantially a right angle and arranged to swing in a recess of the head. 45 This draw-bar rests and slides between the usual top and bottom guides and is retained by a bolt or pin *h* normally entire, but shown broken in Fig. 2.

On the end of the car-body are horizontal 50 posts *n n*, having flanges by which they are

secured to the car-body by bolts or screws *o o* and at their outer ends bearings in which is revolvably mounted the double crank-bar *m*, to the longer arm of which is attached a chain *l*. On the dead-wood *p*, protected by the buffer-plate *q*, are mounted two similar oppositely-disposed upright brackets *b b*, secured by bolts *e* and having in their upper ends journal-bearings in which is fitted a round-headed bolt *c*, retained at its opposite end by 60 a pin or key *d*, and on this bolt is mounted a bell-crank lever *a*, having one arm provided at its outer end with a ring in which is secured the lower end of a chain *l* and its other arm projecting downward and backward. At 65 attached to the ring in the end of the lever *a* is a second and preferably stronger chain *k*, which bears at its lower end a coupling-pin *j*, arranged to enter the hole in the draw-head and to engage the rearwardly-extending arm 70 of the knuckle *r* and prevent it from swinging forward until it is desired to release the coupling. The downwardly-projecting arm of the lever *a* reaches nearly to and is substantially centrally above the draw-bar *i* and 75 is arranged to swing in an opening in the dead-wood and is limited in its backward movement by a stud *f*, secured to the car.

On the draw-bar *i* is a post *g*, resting normally in a recess in the car-body and whose 80 extreme forward movement, while the draw-bar or its bolt remains intact, will not pass the car-front. Hence it will be seen that the parts will operate in the ordinary manner in coupling and uncoupling and the bell-crank 85 lever *a* will simply move with the other parts, performing no distinct function. When, however, the draw-bar becomes detached, as by breaking of the bolt *h*, as suggested in Fig. 2, or from other causes, it will be drawn out 90 of its position, when the post *g* will engage the lower arm of the bell-crank *a* and swing it forward, thus rocking the upper arm upward and drawing the pin *j*, thereby uncoupling the cars and preventing the draw-head 95 from being pulled out of position so as to fall on the track, and as the cars separate the air-brake tubes will be separated, thus allowing the brake to set and simultaneously by the escape of air notify the engineer. 100

Having thus described our invention, what we claim, and desire to secure by Letters Patent, is—

In a car-coupler of the kind specified, the combination with the draw bar and head, and the coupling-pin, of a rocking lever pivoted between its ends in supports adjacent to the draw-bar, having one end flexibly connected with the coupling-pin, and its other resting adjacent to the draw-bar, and a post connected with the draw-bar and arranged to engage the free end of said lever when the draw-bar

moves forward beyond its extreme normal position, to rock said lever and draw said pin, substantially as shown and described. 15

In testimony that we claim the above we hereunto set our hands in the presence of two subscribing witnesses.

FRANK R. MOORE.
EDWARD MCSWEENEY.
CHARLES SCHLEY.
